UNITED STATES PATENT OFFICE.

SAMUEL M. LANGSTON, OF CAMDEN, NEW JERSEY.

BOX-COVERING MACHINE.

1,054,427.

Specification of Letters Patent. Patented Feb. 25, 1913.

Application filed August 14, 1909. Serial No. 512,883.

To all whom it may concern:

Be it known that I, SAMUEL MACDONALD LANGSTON, a citizen of the United States, and a resident of Camden, in the county of 5 Camden and State of New Jersey, have invented a new and Improved Box-Covering Machine, of which the following is a full, clear, and exact description.

This invention relates to machines for applying paper covers to boxes, cartons or the like, and severing the covering into sections, each section being sufficient for a single box or carton. In machines of this character it is customary to provide a rotatable support 10 or form for the box or carton and to deliver the covering material past a cutter to the support or form. The support or form is usually adjustable in respect to the cutter so as to vary its distance therefrom, and the 15 cutter is ordinarily operated intermittently so as to subdivide the covering material into sections of uniform length.

One of the main features of my invention involves the supporting and rotating means 20 for the box support or form, so that the position of the latter may be adjusted at will without interfering with the continuous and uniform rotation.

A further feature of my invention relates 25 to the mechanism for operating the cutter automatically in proper synchronism with the box form or manually and independently of the box form.

Reference is to be had to the accompanying 30 drawings, forming a part of this specification, in which similar characters of reference indicate corresponding parts in all the figures, and in which—

Figure 1 is a side elevation of a machine 35 constructed in accordance with my invention; Fig. 2 is a transverse section on the line 2—2 of Fig. 1; Fig. 3 is a section on the line 3—3 of Fig. 1; and Fig. 4 is a longitudinal section through the spindle of the box 40 support or form and showing the operating means for the latter, said section being taken on the line 4—4 of Fig. 1.

In the specific form illustrated, I employ 45 a body portion or table 10, supported upon suitable legs 11 and having a power supply shaft 12 extending along the length thereof and below the top. Adjacent to one end of the table and mounted in suitable bearings in the table top is a shaft 13, hereinafter referred to as the "main shaft." This shaft 50 has a worm wheel 14, shown in dotted lines

in Fig. 2, and meshing with a worm 15 on the power shaft 12. The main shaft 13 is thus continuously rotated at a comparatively slow rate of speed. Rigidly secured 55 to the table and extending outwardly therefrom is an arm 16, for supporting the box form and operating mechanism for the latter. This arm preferably has one end encircling the shaft 13, and closely adjacent 60 the arm and secured to the shaft is a sprocket wheel 17 and a cam 18. The sprocket wheel serves to transmit motion to the box form and the cam serves to operate the cutter. The cutter is adjustable 65 to varying elevations in respect to the table, said cutter being preferably mounted upon the upper end of a vertically disposed rod 19. At the upper end of the rod is a head or cap 20, having oppositely-disposed 70 brackets 21 and 22. The bracket 21 carries a stationary cutter blade 23, while the bracket 22 carries a rock shaft 24. The rock shaft carries an arm 25 having a movable cutter blade 26 and an arm 27, by means of 75 which the rock shaft may be oscillated. The material to be cut passes over the stationary blade 23 and is subdivided by the lowering of the cutter blade 26 past the edge of the stationary cutter blade. 80

For oscillating the rock shaft 24 to automatically or manually raise and lower the movable blade, the table is provided with a bracket 28, to the upper end of which are pivoted two bell crank levers 29 and 36. 85 The lever 29 has a handle 37 at its front end, and intermediate the handle and the pivotal support of the lever, said lever is pivoted to an upwardly-extending rod 30. The upper end of this rod is pivotally connected to the arm 27 of the rock shaft, so 90 that as the handle 37 is raised or lowered, the movable cutter will be simultaneously raised or lowered. The connections between the rod and the arm 27 are such that the rod is normally locked against longitudinal movement in respect to the arm but may be readily adjusted longitudinally in respect thereto. The two bell crank levers are 95 closely adjacent each other and both have forwardly-extending arms and downwardly-extending arms. The handle 37 is on the forwardly-extending arm of the bell crank lever 29, while on the forwardly-extending arm of the bell crank lever 36 there is provided a roller 31 in the plane of the cam 18, so that the roller follows the periphery of 100 105 110

the cam during the rotation of the latter. The depending arm 58 of the bell crank lever 56 has a forwardly-extending extension 59, from the forward end of which a coil spring 60 extends rearwardly to the depending arm 61 of the bell crank lever 29. The ends of this spring are so connected to the two levers that its tension may be adjusted at will, and the spring is of such character that it tends to draw the arm 61 forwardly and the arm 68 rearwardly. A stop 62 on the arm 58 limits this movement, so that the two arms normally remain in the same relative position as shown in Fig. 1. The major portion of the periphery of the cam lies in the arc of a circle of such diameter that the cutter blade 26 is normally raised to its limiting position, but at one point of the periphery of the cam there is a substantially radially-disposed face 32 which permits the roller to drop downwardly to operate the cutter, and almost immediately thereafter raises the cutter to its former position.

It is evident that any raising or lowering of the roller is communicated directly to the cutter, as the two bell crank levers are normally held against relative movement by the spring 60 and stop 62. If the paper be of uniformly good character, the mechanism will operate substantially as though the roller 31 were mounted directly on the lever 29, but in practice, it is found that there is often bad places in the paper which have to be cut out. To accomplish this, the cutter is free to be operated independently of any movement of the cam. By pressing down on the handle 57, the cutter 26 will be operated even though the bell crank lever 56 and its roller remain stationary. The downward movement of the handle 57 merely extends the spring 60, and as soon as the handle is released, the spring immediately raises the cutter to its normal position. The cutter thus operates automatically at every revolution of the box, and may also be worked manually at any time desired, irrespective of the position of the box.

The arm 16 which extends outwardly from the end of the table, carries at its outer end a transverse shaft 33 and an adjustable arm or frame 34. Loosely mounted on the shaft is a sprocket wheel 35, which may be locked to the shaft by a clutch collar 36 on the outer end of the shaft. A chain 37 connects the sprocket wheel 35 with the sprocket wheel 17 on the main shaft, so as to continuously rotate said sprocket wheel 35, but the shaft 33 may be rotated to vary its angular relationship in respect to the cam 18 by pulling out the clutch collar 36. The shaft 33 is not journaled directly in the outer end of the arm 16 but is journaled in a sleeve 38 extending transversely through the arm. The sleeve termi-

nates at its outer end in a clamp comprising two arms 39, 39, engaging the opposite sides of the secondary arm 34. A nut 40 is threaded on to the sleeve 38 opposite to the clamping arms and by tightening this nut the sleeve may be drawn longitudinally through the arm 16, so that the clamping arms 39, 39, will bind the arm or frame 34 against the side of the arm 16 and lock the two rigid in respect to each other. This nut may be provided with an outwardly-extending handle 41 to facilitate the rotation thereof and permit the arms 16 and 34 to be quickly adjusted in respect to each other.

The frame or arm 34 is formed of two opposed substantially channel-shaped members 42, 42, connected at their upper ends by a journal box 43 and at their lower ends by a transverse member 44. Mounted in the journal boxes is the spindle 45 of the box support or carrier, and upon this spindle is a sprocket wheel 46. Upon the shaft 33 is a sprocket wheel 47 in the plane of the sprocket wheel 46, and at the lower end of the frame 34 and adjacent to the transverse member 44 there is a sprocket wheel 48 carried in vertically adjustable bearings. A chain 49 extends over the sprocket wheels 46 and 48 and engages with the sprocket wheel 47. It may be retained in engagement with the latter by a small idler 50, shown in dotted lines in Fig. 1. The bearings of the lower sprocket wheel 48 are carried by a longitudinally movable rod 51, and are drawn downwardly under tension by a spring 52, so that the chain will remain taut at all times, irrespective of any relative adjustment of the arm 34 in respect to the arm 16. For protecting the gearing and to prevent accidental injury to the workmen, the journal box 43 may carry a covering 53 over the sprocket wheel 46, the side members 42 of the arm 34 may carry a side plate 54, and the arm 16 may carry a casing 55 over the chain 37 and its sprocket wheels. The spindle 45 which carries the box form or box support, may be adjusted longitudinally through the upper end of the arm 34 by loosening a collar 63 shown particularly in Fig. 4.

Any suitable box support or box form may be secured to the spindle 45, so as to rotate therewith. The specific construction of the box form or support constitutes no portion of the present invention, it being understood that any construction may be employed for supporting a box substantially as illustrated in dot-and-dash lines in Fig. 1.

During the operation of the machine power is transmitted from the main shaft through the chains 37 and 49 to the spindle, so as to rotate the latter and wrap the box covering upon the box. The cutter intermittently descends to subdivide the covering

into sections of appropriate length for the box being covered. The distance to which the cutter blade is raised may be varied by varying the adjustment of the rod 30 and 5 the arm 27, and the position of the box form in respect to the cutter may be readily varied by swinging the arm 34 about the shaft 33 as a center or by bodily raising or lowering the arm 34 in respect to said shaft. An 10 adjustment of the position of the spindle 45 does not necessitate any adjustment whatsoever of the driving means for the latter automatically adjusts itself during the movement of the arm.

15 Having thus described my invention, I claim as new and desire to secure by Letters Patent:

1. A box-covering machine, comprising a main shaft, a cam secured thereto, a cutter 20 including a movable cutter blade, a pivoted arm having operative engagement with said cam, a second arm, connections between said second arm and said movable cutter blade for operating the latter, and connections between said first-mentioned arm and said second-mentioned arm to operate the cutter upon the rotation of the cam or to permit of the operation of the cutter independently of the cam.

30 2. A box-covering machine, comprising a main shaft, an outwardly-extending arm, a second arm longitudinally adjustable in respect to the first-mentioned arm, a box support carried by said second-mentioned arm, 35 and driving connections extending along said arms for rotating said box support from said shaft.

3. A box-covering machine, comprising a main shaft, an outwardly-extending arm, a second arm longitudinally adjustable in respect to the first-mentioned arm, a box support carried by said second-mentioned arm, 40 driving connections extending along said arms for rotating said box support from said shaft, a cutter, and means for intermittently operating said cutter from said shaft.

4. A box-covering machine having a frame, an arm extending outwardly therefrom, a sleeve extending through the outer end of said arm, a second arm adjustably secured to said sleeve, a shaft extending through said sleeve, means for driving said shaft, a box support at one end of said second-mentioned arm, and means for rotating said box support from said shaft.

5. A box covering machine, comprising a frame or table, an arm extending outwardly therefrom, a sleeve extending through the outer end of said arm and having clamping members, a second arm adjustably secured to the first-mentioned arm by said clamping members, a shaft extending through said

sleeve, means for driving said shaft, a box support at one end of said second-mentioned arm, and means for rotating said box support from said shaft.

6. A box covering machine, comprising a supporting table or frame, an arm extending outwardly therefrom, a second arm carried by the first-mentioned arm and adjustable in respect thereto, a box carrier mounted on said second-mentioned arm, a shaft adjacent the intersection of said arms, driving connections for said shaft and extending along the first-mentioned arm, and driving connections for said box support and extending along the second-mentioned arm from said shaft.

7. A machine of the class described, comprising a frame or table, a stationary arm extending outwardly from said table, a second arm pivoted to the outer end of the first-mentioned arm and extending substantially vertically, a shaft journaled on said table, a shaft at the intersection of said arms, a spindle at one end of the second-named arm and adapted to carry a box support, driving connections between the two first-mentioned shafts, and driving connections between the second-mentioned shaft and the spindle.

8. A machine of the class described, comprising an outwardly-extending arm having a member extending transversely therethrough and terminating at its outer end in clamping arms, a second arm extending between said clamping arms and supported thereby, means for moving said member longitudinally to lock said arms rigid in respect to each other, a spindle carried by the last-mentioned arm and adapted to carry a box support, and means for rotating said spindle.

9. A box covering machine having an outwardly-extending arm, a second arm adjustably secured thereto, a shaft at the intersection of said arms, means extending along the first-mentioned arm for driving said shaft, sprocket wheels adjacent opposite ends of the second-mentioned arm, a sprocket wheel on said shaft, a chain extending over the two first-mentioned sprocket wheels and in engagement with the last mentioned sprocket wheel, a spindle rotated by one of the two first-mentioned sprocket wheels, and means for adjusting the position of the other of the two first-mentioned sprocket wheels to maintain the chain taut.

In testimony whereof I have signed my name to this specification in the presence of two subscribing witnesses.

SAMUEL M. LANGSTON.
